SWINGABLE AND VERTICALLY ADJUSTABLE
BED TRAY

Philip G. Sarkus, Donora, Pa.

Application October 20, 1951, Serial No. 252,304

5 Claims. (Cl. 311—27)

1 The present invention relates to a swingable and collapsible mounting for a tray which is particularly suitable for beds.

While trays have been used in the past with legs which are adapted to rest on a bed mattress or with means for attachment to posts of hospital beds and the like, these have the serious disadvantage of being unsightly and not being readily movable out of sight by the occupant of the bed, nor adjustably movable to selective positions overhanging the bed or the space alongside the bed.

An object of the present invention is to provide a pivotal tray supporting means which will permit a wide range of adjustment of the tray by one lying in bed and useful for supporting food, books, radios or the like, and which is swingable and foldable or collapsible in a manner so that it is positioned rearwardly of the headboard of the bed and thus completely out of sight when not in use.

A more specific object of the present invention is to provide a bed tray mounting which is movable from a horizontal position forwardly of the bed to a vertical position rearwardly of the bed without the need of substantial clearance between the bed and the adjoining side or end wall, and which can be easily and quickly moved out of sight in a folded position by the bed occupant when the tray is no longer in use.

Other objects and advantages of the present invention will become apparent from a study of the following description taken with the accompanying drawings wherein:

Figure 1 is a plan view of the bed tray mounting embodying the principles of the present invention and showing the tray in a horizontal position forwardly of the headboard in position for use by the occupant;

Figure 2 is a rear elevational view of the vertically adjustable mounting for the tray support as viewed from the rear of the headboard upon which it is mounted;

Figure 3 is an enlarged fragmentary vertical cross-sectional view of the vertical adjusting means shown in Figure 2, taken along line III—III of Figure 1;

Figure 4 is an enlarged fragmentary view partly in cross-section of the upper part of one of the vertical supporting racks shown in Figure 2;

Figure 5 is an enlarged transverse, cross-sectional view taken along line V—V of Figure 1;

Figure 6 is an enlarged end elevational view taken along line VI—VI of Figure 1;

Figure 7 is an enlarged cross-sectional view taken along line VII—VII of Figure 1;

Figure 8 is an enlarged elevational view similar to Figure 2, but showing the tray in its folded position rearwardly of the bed headboard and completely out of sight of the bed occupant;

2 Figure 9 is a vertical cross-sectional view taken along line IX—IX of Figure 8, and

Figure 10 is an enlarged fragmentary, perspective view of the slide bolt locking means showing the position of the supporting parts when the bed tray is in the operative position forwardly of the bed.

Referring more particularly to Figure 1, numeral 1 denotes a tray of any suitable metal or plastic material supported centrally on the bottom thereof by an integral pedestal or base portion 2 which forms a vertical extension of an angular rod 3 having a supporting bracket 4 intermediate the rod and tray for additional support of the tray. Rod 3 is pivotally connected to a link 5 which in turn is pivotally connected to a telescoping rod 6 formed of telescoping parts 6a and 6b. Part 6b has longitudinally extending grooves into which are guided the ends of a cross pin 6c which extend through telescoping part 6a as shown more clearly in Figure 5. Thus the telescoping rod 6 may be extended or shortened as desired to move the tray away from or toward the bed occupant. The other end of rod 6 is pivotally mounted on a horizontally slidable rod or bolt 8 which has an integral pin 9 which is guided by a groove 10 formed in a slide bolt casing or housing 11. Casing 11 is rigidly secured to a vertically adjustable support 12 having vertically extending grooves through which there extend racks 13 having lower inwardly bent integral end portions 13b and upper inwardly bent separate end portions 13c which are secured by screws 14 or other suitable fastening means to the rear surface of the headboard B of the bed.

Figure 3 shows the vertical adjusting means for support 12 which comprises slidable rods or pawl 15 to which are secured wings or ears 16 having end portions through which there extends screws 17 partly surrounded by a helical spring 18. Outwardly struck ear portions 12a of housing 11 serve as guides for rods 15. Thus it will be seen that the occupant may extend his hand behind the headboard and grasp the ears 16 and push them together against the action of spring 18 and in so doing unseat the ends of rods 15 from rack teeth 13a in which they are seated. Upon such withdrawal of the rods 15, the slide bolt casing or housing 11 may be selectively moved to any desired vertical position so that upon release of the wings 16, rods 15 are seated in a new pair of rack teeth 13a, thus providing the bed tray with a wide range of vertical adjustment.

In operation, when the bed tray is in the operative position shown in Figure 1, that is, in a horizontal position forwardly of the occupant of the bed and overhanging the mattress, the tray 1 may be moved forward or away from the occupant by virtue of the telescoping connection of rod 6.

If it is desired to securely lock the bed tray in this position, a pin 20, suspended from chain 21 mounted on a chain support bracket 22, may be used by extending pin 20 through a hole extending vertically through the housing 11 and through a corresponding hole in slidable bolt 8, to prevent accidental lateral sliding movement of bolt 8. Even without pin 20, the tray is locked into the position shown in Figure 1 by virtue of the shape of groove 10 inasmuch as the groove has a vertical and lateral offset as shown to the right of Figures 1 and 2 into which pin 9 is guided and held as shown more clearly in Figure 10. Pin 9 has a horizontally extending wing portion at the top thereof which is engageable against the vertical wall of support 12 so as to accurately and rigidly support rod 8 in such position that the tray 1 will be in a horizontal position.

When the tray is no longer needed, it may be moved out of sight of the bed occupant, that is, rearwardly of the headboard, by swinging tray 1 through an angle of 270° to the dash-and-dot line position shown in Figure 1 by virtue of the connecting link 5. Thereafter, upon removal of pin 20 from the registering slots in housing 11 and bolt 8, it will be possible to move rod 6 towards the occupant, then vertically upwardly to enable pin 9 to move away from the right hand offset of groove 10 through an angle of 90° to a position so that it will be slidably horizontally throughout the length of groove 10. Rod 6 is then pivotally moved in a vertical plane through an angle of 270° to the collapsed position shown in Figure 8. When in this position, the angular rod 3 may be supported by a supporting bracket or hanger 12b extending from support 12. Groove 10 has a cutout at the left hand end thereof as shown in Figure 8 for allowing the tray to be lifted from the support or hanger 12b. Thus when the tray support is collapsed to the position shown in Figure 8, the tray will extend vertically behind the headboard B and thus it, as well as the supporting means, will be completely out of sight.

Of course, when the occupant desires a tray, he will reach his hand rearwardly of the headboard and will move the tray and supporting assembly in the opposite sequence of that described so as to move the tray from the position shown in Figure 8 to that shown in Figure 1.

If desired, the portion of rod 3 near link 5 may be made extendible by providing telescoping parts therefor.

Thus it will be seen that I have provided a highly efficient, swingable bed tray support which allows adjustment of a bed tray horizontally as well as vertically to a wide variety of positions forwardly of the bed, and which mounting is so constructed as to enable swinging of the bed tray to a position rearwardly of the headboard without the necessity of extra clearance either alongside the bed or behind the bed with respect to adjoining walls, and which support is collapsible to occupy a position rearwardly of the headboard and completely out of sight when not in use.

While I have illustrated and described a certain specific embodiment of my invention, it will be understood that this is by way of illustration only, and that various changes and modifications may be made within the contemplation of my invention and within the scope of the following claims.

I claim:

1. In combination with a bed headboard, swing-

able mounting means mounted on the rear surface of said headboard and including a horizontally slidable bolt means having pivotally connected thereto and pivotally movable arms forming a tray supporting means, a tray supported by said supporting means and being swingably mounted in a horizontal plane as well as in a vertical plane in a manner so that it may be moved to the rear of the headboard completely out of sight.

2. A swingable bed tray mounting for support on the rear surface of the headboard of a bed, said mounting comprising slide bolt means within a housing including a pin-and-slot connection for enabling the bolt to be turned 90° about its axis and to be slidably moved longitudinally of the housing, a rod pivotally mounted on an end of said bolt, and a second rod pivotally mounted on the opposite end of said first mentioned rod, and a tray supported by said second rod, and connecting means between said first and second rod to enable pivotal movement of said second rod throughout an angle of 270°, said first rod being pivotally movable with respect to said bolt throughout an angle of about 270°, whereby said tray may be moved from a horizontal position forwardly of a bed to a vertical position rearwardly of the headboard of said bed.

3. Apparatus as recited in claim 2, together with means for vertically adjusting the position of said housing with respect to said headboard and wherein said first rod includes telescoping parts for enabling adjustable movement of the tray toward or away from the head board when in the horizontal position forwardly of the bed.

4. Means for adjustably mounting a tray with respect to the headboard of a bed, comprising a housing which is attachable to the rear surface of the headboard and having a slotted guideway in which is slidably mounted a slide bolt having an integral pin adapted to be guided by the slot formed in said guideway, said groove extending horizontally and having a vertical position, an arm pivotally connected to one end of said bolt, a link connected to the opposite end of said arm, a second arm pivotally connected to said link, and a tray supported by said second arm and movable through an angle of 270° when in the horizontal position and through an angle of 270° when in a vertical plane through pivotal movement of said arms and link.

5. Apparatus as recited in claim 4, together with rack means extending through said guideway for attachment to the rear surface of the bed headboard, and a pair of inwardly movable rods whose extreme ends are engageable in grooves of said rack means to enable vertical adjustment of said guideway with respect to said rack means for adjusting the vertical position of the tray when swung to the operative position.
